UNITED STATES PATENT OFFICE.

ICHIRO NODA, OF BROOKLYN, NEW YORK.

AMUSEMENT DEVICE.

Application filed January 6, 1928. Serial No. 244,937.

This invention relates to amusement devices and has particular reference to an apparatus in which the skill of participants in hitting a target automatically dispenses 5 prizes for delivery to the participants.

The invention aims for an object to provide an amusement device or game apparatus for use in public amusement parks, which includes a plurality of targets and a compartment corresponding to each target containing a vertical stack of articles constituting prizes together with means operable by the target when hit for ejecting the lowermost article of the stack contained 10 in the compartment corresponding to the target.

The invention furthermore aims to provide in a device to the character set forth a plurality of targets in spaced rows of tiers 20 in which the targets nearer to the participants are of lesser area than the targets which are at a greater distance from the participants so that the skill required to hit the targets is approximately equalized.

25 The invention comprehends in an amusement device or game apparatus, a plurality of targets, a compartment corresponding to each target containing a vertical stack of articles representing the prizes, a delivery stall adjacent the lower end of each compartment, a normally retracted plunger movable to effect the ejection of the lowermost article, and a connection between the target and the plunger for moving the plunger when the 35 target is hit, to discharge the articles into the delivery stalls.

The invention furthermore embodies means for returning the balls or projectiles with which the targets are hit by the participants, to a common point where they may be delivered to the participants.

40 Other objects reside in the simplicity of construction of the apparatus, the economy with which the same may be produced and 45 installed, and the highly amusing character of the game.

With the above recited and other objects in view, reference is had to the following description and accompanying drawings in 50 which there is exhibited one example or embodiment of the invention, while the appended claims define the actual scope of the invention.

In the drawings—

Figure 1 is a perspective view of the 55 apparatus;

Fig. 2 is a longitudinal sectional view therethrough;

Fig. 3 is a fragmentary horizontal sectional view taken approximately on the line 60 3—3 of Fig. 2, and

Fig. 4 is a fragmentary transverse sectional view taken approximately on the line 4—4 of Fig. 2.

Referring to the drawings by characters of reference, 10—10 designate the side walls of the cabinet, 11 the rear wall and 12 a bottom wall which inclines forwardly and downwardly from the rear wall to the front of the cabinet. A padded backing element 13 is 70 attached to the rear wall and similar padded backing elements 14 and 15 are supported in forwardly spaced relation to the element 13. The element 14 is spaced in a plane below the element 13 and the element 15 75 in a plane below the element 14. A plurality of targets 16 arranged in transversely spaced relation and in front of the element 13 are provided and the targets 16 are of greater area than a plurality of trans- 80 versely spaced targets 17 arranged in front of the backing element 14. A plurality of transversely spaced targets 18 of lesser area than the targets 17 are arranged in front of the backing element 15. Each target is 85 supported by a vertical lever 19 which is fulcrumed intermediate its ends on a transverse rod 20. At the front of the cabinet a plurality of compartments 21 are arranged in a transverse row and are covered pref- 90 erably by a transparent front panel 22. A horizontal shelf 23 is supported between the side walls 10 of the cabinet and is spaced below the lower open ends of the compartments a distance approximately equal to the 95 height of one of a stack of articles A which are positioned in the cabinet and which constitute prizes adapted to be given to the participants of the game who succeed in hitting the various targets. Adjacent the 100 lower end and slightly in advance of each compartment, is a delivery stall 24, while supported for sliding movement on the shelf 23 in rear of each compartment is a plunger 25 having a plunger rod 26 slideable in a 105 bearing 27. Each plunger rod is normally retracted or moved rearwardly by a coiled contractile spring 29 until its rear end en-

gages with an upstanding transverse wall 30 at the rear edge of the shelf 23, in which position the forward end of the plunger 25 is disposed directly in rear of the lowermost 5 article of the stack, which articles gravitationally feed downwardly onto the shelf. The lower end of each target lever 19 is connected by a link 31 to one of the plunger rods 26 so that a ball or other projectile B 10 thrown or otherwise projected by the participant striking one of the targets 16, 17 or 18, causes the plunger 25 to be projected forwardly to engage with and push the lowermost article of its stack forwardly 15 beyond the forward edge of the shelf 23 where it gravitates into the delivery stall 24. As the target moves rearwardly under the impact of the ball or projectile B, it is arrested in its movement by one of the 20 padded background elements 13, 14 or 15, and it is obvious that the ball will descend on to the inclined bottom wall 12. From this point the balls or projectiles B roll toward the front of the cabinet where they come 25 to rest against a transverse front strip 32. As soon as the impact of the ball has moved the target and swung the target lever 19 rearwardly, and the plunger has performed its function to effect the lowermost article 30 of the stack, the spring 29 will function to retract the plunger to its normal position and through the medium of the link 31 will move the target and target lever to a normal vertical position.

35 It is proposed within the purview of the invention to dispose a counter suitably spaced in front of the cabinet from which point the participants throw or otherwise project the balls or projectiles B against the targets. By having the rear row of 40 targets 16 of a greater diameter than the next adjacent front row and the intermediate row of targets 17 of a greater diameter than the targets 18 of the front row, the skill required to strike the targets is approximately equalized. When a participant 45 hits a target and one of the articles A is dispensed or projected from the stack into one of the stalls 24, the attendant of the 50 game or device removes the article from the stall and hands it to the participant as a prize. The balls or projectiles which fail to hit the targets are deflected downwardly by the padded backing elements 13, 14 or 55 15. The attendant removes the balls which gravitate forwardly and gives the desired number to the participants.

60 The games while particularly designed to use packages of cigarettes as prizes, may also be used for prizes of a different nature and of various values, in which instance certain of the targets may be constructed in such a manner as to render those corre-

sponding to the more valuable prizes harder to hit than those which correspond to the less valuable prizes.

What is claimed is:

1. In an amusement apparatus, a cabinet including side walls, a forwardly and downwardly inclined bottom wall, a superposed horizontal partition, transversely spaced compartments disposed over the horizontal partition and each containing a vertical stack of articles constituting prizes, the lower ends of the compartments being spaced above the partition a distance equal to the depth of one of the articles, a delivery stall in front of each compartment and below the forward edge of the partition, transversely spaced targets mounted in the rear portion of said cabinet and projecting upwardly therefrom and a plunger operatively connected with each target and movable over the upper surface of the partition by the target when hit by a projectile for engaging with and effecting the ejection of the lowermost article of the stack into the delivery stall. 70 75 80 85

2. In an amusement apparatus, a cabinet including side walls, a forwardly and downwardly inclined bottom wall, a superposed horizontal partition, transversely spaced compartments disposed over the horizontal partition and each containing a vertical stack of articles constituting prizes, the lower ends of the compartments being spaced above the partition a distance equal to the depth of one of the articles, a delivery stall in front of each compartment and below the forward edge of the partition, transversely spaced targets mounted in the rear portion of said cabinet and projecting upwardly therefrom, a plunger operatively connected with each target and movable over the upper surface of the partition by the target when hit by a projectile for engaging with and effecting the ejection of the lowermost article of the stack into the delivery stall and means in the rear of each target for deflecting the projectiles downwardly onto the inclined bottom wall for gravitational movement to the front of the cabinet. 90 95 100 105 110

3. In an amusement apparatus comprising a plurality of vertical stacks of articles constituting prizes and means for ejecting the lowermost article from the stack including a plurality of rows of targets arranged in rearwardly spaced tiers, the targets being of progressively larger area toward the rear. 115 120

Signed at Coney Island, in the county of Kings and State of New York, this third day of January, A. D. nineteen hundred and twenty eight.
